[57] ABSTRACT

A modified picking mechanism is disclosed for interrupting actuation of a picker stick at predetermined intervals to stop the insertion of filling yarn into the fabric for a predetermined number of picks. A pick shaft is disclosed wherein a pick arm that is associated with the picker stick is journaled around a reduced diameter portion of the pick shaft for free movement thereabout. A spring biased pawl attached to the pick arm is normally presented for contact with a protuberance from the pick shaft so as to actuate the picker stick to propel the shuttle across the loom. At predetermined intervals, a box motion indicator causes an indicator rod to be raised which pivots a lever into engagement with the pawl and causes the pawl to rotate out of engaging position with the protuberance from the pick shaft. The pick shaft then reciprocates freely whereby the picker stick remains motionless and no fill yarn is inserted.

LOOM PICK CONTROL MECHANISM

BACKGROUND OF THE INVENTION

It is often desirable during the weaving of fabric to produce an intended "thin spot" in the fabric. The phrase "thin spot" is herein defined as a section of woven fabric where filling ends are omitted and only warp ends are present. Such thin spots are periodically produced in the continuous manufacture of towels, tablecloths, washclothes and the like which have a fringe at each end thereof. Hence, after the fabric is woven, a cut across adjacent thin spots in the fabric produces the article with a warp-wise fringe at each end of the article. Obviously, the continuous weaving followed by cutting across the thin spots is a much more economical means of producing the article than individual manufacture of the article with the fringe. Box looms utilizing a magazine of normally four boxes for holding filling yarn and supplying same to the picker can produce a thin spot in the fabric when the loom is programmed to provide an empty box in the way of the picker stick during the prescribed period of time. For a single shuttle loom, however, and even for the box looms where a four color filling pattern is being produced, or for that matter, where all of the available boxes are being utilized, there is no presently available system that can be economically provided to enable the loom to cease inserting filling yarn for a predetermined number of picks during weaving. While there are systems available for accomplishing this purpose, each of these systems is deficient either in the modus operandi or in the cost of equipping a loom with the apparatus of the system.

Such systems are exemplified in the prior art by U.S. Pat. Nos. 3,227,186 to Baugham; 1,171,249 to Reynolds and 1,651,338 to Brown. Different systems for interrupting the supply of filling yarn to the loom are disclosed in the aforementioned patents. None of the teachings of these patents, however, either alone or in combination anticipate or suggest the present invention, which will be hereinafter described in detail.

SUMMARY OF THE INVENTION

It is an object of the present invention to provide a modification for a loom to permit periodic interruption of the supply of filling yarn to the fabric being woven.

A further object of the present invention is to provide a system for periodically deactivating the picker stick of a loom so as to prevent the filling yarn from being propelled across the fabric being produced.

Still further, another object of the present invention is to provide an improved system for producing intended thin spots in fabric.

Generally speaking, the present invention relates to a pick control mechanism for a shuttle loom comprising a picker stick; a driving mechanism for affording operative motion to said picker stick; a mechanical linkage connecting said driving mechanism and said picker stick, said mechanical linkage normally operatively connecting said drive mechanism and said picker stick; and control means associated with said mechanical linkage to operatively disconnect said driving mechanism from said picker stick during predetermined intervals.

Hence, the present invention broadly construed, operates to interrupt the driving force to the picker stick at desired intervals to produce a section of the fabric being woven where the pick ends are omitted. Under normal operation of the present invention as the pick shaft reciprocates, a protuberance from the pick shaft engages a pawl that is associated with and extends outwardly from the mechanical linkage that operatively connects the pick shaft and the picker stick. The force of the reciprocating picker shaft is thus transmitted through the mechanical linkage to the picker stick whereby the picker stick pivotally moves forward, strikes the shuttle and throws it across the loom. After a predetermined number of picks have been inserted into the fabric, the box motion indicator associated with the loom causes an indicator rod to be raised. The indicator rod is operatively associated with a lever that is

5 moved into engagement with the pawl to pivot the pawl out of engageable position with the protuberance from the pick shaft, whereby as the pick shaft reciprocates, it does not engage the pawl and hence does not transmit driving motion to the picker stick. After a predetermined number of picks have been omitted, the indicator rod is depressed whereby the lever moves out of engagement with the pawl which permits the pawl spring to again bias the pawl into engageable position with the protuberance to resume normal weaving operations.

10 The present invention is extremely unique, in that, it is both simple and economical to install on a new loom and may likewise be economically added to an existing loom with only minor modifications thereto.

15 BRIEF DESCRIPTION OF THE DRAWINGS

FIG. 1 is a perspective view of a portion of a loom illustrating operative elements of the present invention.

FIG. 2 is a partial cross sectional view taken along line II-II of FIG. 1 to show the relative position of the operative components of the present invention during normal weaving.

FIG. 3 is a partial cross sectional view taken along line II-II of FIG. 1 to show the relative position of operative elements of the present invention during interruption of picking.

25 FIG. 4 is an exploded side view of the spring biased pawl of the present invention.

FIG. 5 is a side view of a lug shaft sleeve and washer according to the teachings of the present invention.

30 DESCRIPTION OF THE PREFERRED EMBODIMENTS

Referring to the Figures, preferred embodiments of the present invention will now be described in detail. In FIG. 1, that portion of a loom is presented such as is necessary to describe the operative elements and operation of the present invention. Framework 10 of the loom supports a picker stick 12 that inserts the filling yarn via a shuttle (not shown) between the warp yarns of the fabric being produced. The picker stick 12 is conventional and will not be further discussed in detail, per se, or as to its pivotal mounting to frame 10. Normally, upon actuation by the driving mechanism for the loom, the picker stick 12 is suddenly pivoted in the direction of the one headed arrow so as to provide impact to the shuttle and propel it across the loom.

40 45 Picker stick 12 is shown associated with a mechanical linkage generally indicated as 15 which in turn is associated with a pick shaft 16. Mechanical linkage 15 comprises lug strap 13, lug 14 and pick arm 20. Pick shaft 16 is shown to have a reduced diameter end 16' which is received in a journal 18 mounted to frame 10. Adjacent journal 18 is a pick arm 20 which forms a part of linkage 15. On a conventional loom, pick arm 20 is normally integral with the pick shaft 16 such that, as pick shaft 16 reciprocates, pick arm 20 likewise reciprocates and through the normal connections causes transmission of a driving force to the picker stick 12.

50 55 According to the teachings of the present invention, however, the reduced diameter portion 16' of pick shaft 16 extends through pick arm 20, and pick arm 20 is freely rotatably received around reduced portion 16'. Hence, without consideration of any further association, pick arm 20 would stand idle during reciprocation of pick shaft 16. To operatively connect the mechanical linkage 15 with the pick shaft 16 and thus permit transmission of force to picker stick 12, a tubular collar 60 65 22 is permanently secured to pick arm 20 as by welding or as an integral part thereof. Collar 22 has an opening therethrough in which is received a shaft 26 having a pawl 28 intermediate the length thereof. As is best seen in FIG. 4, a spring means 30 is positioned along shaft 26 between pawl 28 and a terminal flange 32. Pawl 28 is provided with an upper end 29 for engagement with pick shaft protuberance 17 and a lower end 29' for engagement with lever 44, the purposes of which will be described hereinafter.

70 75 Shaft 26, as mentioned earlier, is received within the opening of collar 22. Shaft 26, however, passes completely through

collar 22 and is secured at the opposite end thereof by a washer 21 and a sleeve 23. Both washer 21 and sleeve 23 have a flat surface area 21' and 23' respectively (see FIG. 5). Additionally, sleeve 23 has a set screw 25 therein that engages shaft 26 to prevent rotation of shaft 26 with respect to sleeve 23. Flat surfaces 21' and 23' engage a flat surface of on pick arm 20 to prevent rotation of washer 21 and sleeve 23 when pawl 28 is engaged by protuberance 17 whereby the force produced by reciprocation of pick shaft 16 is transferred from pawl 28 through collar 22 to pick arm 20.

Pick shaft 16 has extending outwardly therefrom an arcuate protuberance 17. Protuberance 17 is preferably integral with pick shaft 16 and as may be seen in FIGS. 2 and 3 has a contact face 17' and a shoulder 17'', which under normal weaving conditions, form a "V" for contact with the forward beveled end 29 of pawl 28. Hence, as pick shaft 16 reciprocates, protuberance 17 moves into and out of contact with the beveled forward end 29 of pawl 28 to transmit a driving force to picker stick 12 through collar 22, pick arm 20, lug 14 and lug strap 13.

A mounting 40 is secured to the loom frame 10 generally below pawl 28. Mounting 40 has an opening 41 extending through a portion thereof. Opening 41 rotatably receives a shaft 42. Shaft 42 has secured to one end thereof a lever 44 which extends upwardly in the general direction of pawl 28. During normal weaving conditions as is depicted in FIG. 2, the upper end 45 of lever 44 rests adjacent the lower end 29' of pawl 28. Shaft 42 further is equipped with rod arm 46 at the end opposite lever 44. Rod arm 46 has attached thereto and extending upwardly therefrom an indicator rod 48, the opposite end of which is operatively associated with a normal box motion indicator 50 that is provided on the loom. Box motion indicator 50 programs the insertion of a particular number of picks after which the picking motion is interrupted for a predetermined number of picks to produce the thin spot in the fabric.

Under normal operating conditions, pick shaft 16 receives power from a conventional cam system (not shown) and reciprocates as shown by the two-headed arrow. During each cycle of reciprocation the "V" between contact face 17' and shoulder 17'' of arcuate protuberance 17 engages the forward face 29 of pawl 28 to cause pick arm 20 to pivot around reduced end 16' of pick shaft 16. The pivotal motion of pick arm 20 causes the lower end 20'' of pick arm 20 to pull lug 14 and lug strap 13 in the direction of the single headed arrows. Hence, since linkage 15 is connected to picker stick 12, a driving force is provided for forward pivotal movement of picker stick 12 which drives the shuttle across the loom to insert the fill yarn between the warp yarns of the fabric being produced.

After a predetermined number of picks have been laid into the fabric, the box motion indicator actuates a means (not shown) to raise indicator rod 48. Raising of indicator rod 48 causes indicator arm 46 to raise, which in turn rotates shaft 42. As shaft 42 rotates, lever 44 received on the end thereof pivots forward and engages the lower end 29' of pawl 28 (See FIG. 3) which in turn causes the forward beveled end 29 of pawl 28 to pivot against the bias of spring 30 out of position where it would be engaged by contact face 17' and shoulder 17'' of protuberance 17 during each cycle of reciprocation of pick shaft 16. As such, while pick shaft 16 reciprocates, protuberance 17 misses beveled end 29 of pawl 28. Force is thus not transmitted to pick arm 20, pick shaft 16 thus turns freely within pick arm 20 and lug 14, lug strap 13 and picker stick 12 are not moved. Accordingly, the shuttle remains in the shuttle box and fill yarn is not inserted across the fabric.

The indicator rod 48 remains in the raised position during a predetermined time sequence to facilitate the omission of a predetermined number of picks or predetermined number of insertions of fill yarn into the fabric. After the predetermined number of picks have been omitted, the box motion indicator actuates appropriate means to lower indicator rod 48. Rod arm 46 is thus depressed which rotates shaft 42 and disengages lever 44 from lower end 29' of pawl 28. Spring 30 then biases

the forward beveled end 29 of pawl 28 back into position to again be struck by protuberance 17 to permit normal insertion of pick ends into the fabric.

Sections of the fabric produced as described above during 5 the predetermined time sequences for omitting filling ends contain only the warp or longitudinal yarns and thin spots are thus produced. After the fabric has been woven, removed from the loom and further processed as desired, the fabric may then be cut across the thin spots to separate the articles 10 which then possess only a plurality of warp yarns at each end which cooperate to form a fringe for the article.

As mentioned earlier, while the basic utilization of the present invention is a modification for a single shuttle loom, the same adaptation may be incorporated on a multiple shuttle 15 loom. For example, on a four box loom where three colors are being inserted as filling yarns, a thin spot may be incorporated into the fabric by presenting the fourth (empty) box to the picker stick during the time sequence for omission of filling yarn. If, however, four colors are being utilized in the 20 weaving of the fabric, then, of course, there is no empty box to be presented and the thin spot cannot be produced. As such, modification to a multiple box loom to incorporate the apparatus of the present invention thereon will permit production of a thin spot in the fabric regardless of the number of boxes being used. Accordingly, the present invention may be mounted on a multiple box loom as well as a single shuttle loom to be used either in lieu of presentation of an empty box to the picker stick or to be used when full utilization is made of the boxes on the loom.

Having described the apparatus of the present invention in detail in the environment of producing thin spots in fabric, it is obvious that variations and modifications may be made thereto by one skilled in the art without departing from the scope of the invention. Accordingly, the scope of the present invention should be determined only by the claims appended hereto.

What is claimed:

1. A pick control mechanism for a shuttle loom comprising:
a. a picker stick;
b. a driving mechanism for affording operative motion to said picker stick, said driving mechanism comprising a pick shaft and means for reciprocating said pick shaft, said pick shaft having a protuberance secured thereto and extending outwardly therefrom;
- c. a mechanical linkage normally connecting said driving mechanism and said picker stick, said mechanical linkage comprising a pawl normally engaged by said protuberance during reciprocation of said pick shaft to propel said picker stick forward; and
- d. control means associated with said pawl to move said pawl out of the path of travel of said protuberance at such times when it is desired to omit a filling end in a fabric being woven on said loom, said control means comprising a lever movable into and out of engagement with said pawl.
2. A pick control mechanism as defined in claim 1 wherein said pawl is pivotally secured to an arm, said arm being freely swingable about said pick shaft at one end and operatively connected to said picker stick at another end.
3. A pick control mechanism as defined in claim 2 wherein said pawl is spring biased into the path of travel of said protuberance for engagement therewith.
4. A pick control mechanism as defined in claim 1 wherein 65 said control mechanism comprises a shaft mounted on said loom for rotational movement, a lever received on said shaft for movement therewith, said shaft further having means associated therewith for causing rotational movement thereof at a predetermined time.
5. A pick control mechanism as defined in claim 4 wherein 70 said means causing rotational movement to said shaft comprise a box motion indicator and a rod associated with said indicator and said shaft, said rod being actuated by said indicator at a predetermined time to afford rotational movement to said shaft.

6. A pick control mechanism as defined in claim 1 wherein ends of said protuberance and said pawl are constructed so as to insure solid engagement therebetween.
